UNITED STATES PATENT OFFICE.

BENJAMIN F. BARNES, OF ROCKFORD, ILLINOIS, ASSIGNOR TO THE B. F. BARNES COMPANY, OF SAME PLACE.

GRINDING-WHEEL SUPPORT.

SPECIFICATION forming part of Letters Patent No. 665,380, dated January 1, 1901.

Application filed October 18, 1900. Serial No. 32,922. (No model.)

To all whom it may concern:

Be it known that I, BENJAMIN F. BARNES, a citizen of the United States, residing at Rockford, in the county of Winnebago and 5 State of Illinois, have invented certain new and useful Improvements in Grinding-Wheel Supports, of which the following is a specification.

The object of this invention is to construct 10 a grinding-wheel support and means for presenting water to the wheel, the means operated by a pressure of the body of the operator.

In the accompanying drawings, Figure 1 is 15 an isometrical representation of my improved grinding-wheel support. Fig. 2 is a plan view of the water-reservoir and means for raising it. Fig. 3 is a plan view of the base. Fig. 4 is an elevation and partial section. Fig. 5 is 20 a transverse section of the base and water-reservoir.

I am aware that grinding-wheel frames have means attached for presenting water to the revolving wheel, the means being operated by a hand-lever or foot-treadle. In the frames 25 employing a hand-lever the operator neglects to turn off the water, and at various points in grinding more or less water is desired, which necessitates the operator stopping work to move the hand-lever. In frames employing 30 foot-treadles the operator is required to sustain his entire weight upon one foot, while the other foot is employed to operate the treadle to regulate the quantity of water presented to the wheel. The base of my improved 35 grinding-wheel frame consists of the bottom 1, having two sides 2. An opening 3 extends through the bottom in its lengthwise direction. A deflecting-flange 4 extends around this opening, and the rear portion thereof has 40 an outwardly-extending portion 6. A grinding-wheel 7 is supported to revolve in bearings 8 and is driven by a belt connection with the pulleys 9. A hood 10 is supported by the base and has a pivoted extension 11. A tool-rest 12 has an adjustable connection with the base. A base is supported by the front legs 13 and the rear legs 14. To the front face of the front legs are secured bearings 15, between which is pivotally supported a rock-shaft 16. From the rear face of this rock-shaft extends a double cam 17, having a notch or recess 18 at the center of the cam. To the

front face of this rock-shaft is secured a socket having three sections 19, and within each section is secured an arm 20. A bar 21 is pivotally supported in bearings 22 in the front legs, the bearings being in hook form, which permits the removal of the bar. From this bar extend two arms 23, each having a pintle 24, extending inward, and an arm 25 extends downward from this bar and is provided with cross-bar 26, having its ends rounded. A projection 27 extends from the arm 25 and supports a roller 28, which is located in the central notch 18 of the double cam. 65

In bearings 29, formed in the upper portion of the rear legs, is seated a bar 30 in a removable manner and has two rearward extensions 31, each provided with an inwardly-extending pintle 32. These pintles 32 support a bar 33 by the depending arms 34, having a detachable connection with the pintles 32. From the bar 30 extends an arm 35, having a cross-bar 36 at its lower end. A link 37 has its ends forked and provided with open 70 bearings, one end located in connection with the cross-bar of the arm 25 and its other end located in connection with the cross-bar of the arm 35, thereby forming a connection between the arms. 75

A water-reservoir 38 is of a form corresponding to the form of the grinding-wheel 7, but of a larger radius. The ends of this water-reservoir have hooks 39 extending from its front end and hooks 40 extending from its 85 rear end. The hooks of the front end rest upon the pintles 24, and the hooks of the rear end rest upon the bar 34, thereby forming a connection between the bars and the water-reservoir. The rear portion of the water-reservoir 90 has inwardly-extending flanges 41, which are located over the outwardly-extending flanges 6 of the bottom 1. 80

In the construction above described by the movement of the arms 20 the double cam 17 95 will be moved, which will cause the roller to rock the arm upon its pivotal connection with the front legs. This rocking movement will impart a rocking movement to the bars 21 and 33 through the link 37, connecting them, 100 and as the water-reservoir is supported by these bars it will be raised bodily, and the water in the reservoir will be brought in contact with the grinding-wheel, which will ele-

vate it and carry it over into contact with the tool to be ground, and the greater the movement of the double cam the higher will the water-reservoir be raised and more water presented to the grinding-wheel. By employing the double cam a movement of the arms 20 in either direction will elevate the link connection and raise the water-reservoir. The flange 4, depending from the under side of the bottom, guides the water into the water-reservoir, and the flanges 6 and 41 serve to prevent the water from splashing out when thrown by the grinding-wheel. The arms 20 are located beneath the forward end of the base and at a proper height to receive a pressure from the body of the operator, and as soon as the pressure is released the arms will return to their normal position by reason of the weight of the water-reservoir operating upon the link connection with the roller 28 and through it to the double cam 17, which will cause the roller to enter the notch 18, thereby holding the arms in their normal position.

25 By operating the water-reservoir by a pressure of the body the operator can stand squarely on both feet, and his hands are free to attend to the grinding of the tool, and the instant the body-pressure is released the water-reservoir will drop and allow the grinding-wheel to run dry, and the greater the pressure the greater will be the water elevated by the grinding-wheel.

By "lateral" movement of the means for operating the water-supply, I mean a pressure by the operator against the means, which allows the operator to stand upon the floor and have free use of his hands, and by the act of pressing against the means the water is turned on or brought against the wheel.

35 By the term "water-supply" used in the specification and claims, I mean any source by which water is presented to the grinding-wheel, and therefore I do not limit myself to the employment of a water-reservoir.

40 I claim as my invention—

45 1. A grinding-wheel support, comprising a

base, a water-supply, and an arm capable of a lateral movement for regulating the water-supply.

2. A grinding-wheel support, comprising a base, a water-supply, and an arm capable of a lateral movement and an automatic return movement for regulating the water-supply.

3. A grinding-wheel support, comprising a base, a water-reservoir located beneath the base, and means for raising the reservoir and permitting its automatic return.

4. A grinding-wheel support, comprising a base, a water-reservoir located beneath the base, an arm capable of a lateral movement, and a connection between the arm and water-reservoir.

5. A grinding-wheel support, comprising a base, a water-supply, a series of arms having a pivotal support, and a connection between the arms and water-supply.

6. A grinding-wheel support, comprising a base, a water-supply, an arm, a double cam moved by the arm, and a connection between the cam and water-supply.

7. A grinding-wheel support, comprising a base, a water-reservoir, a series of arms, a double cam moved by the arms, and a connection between the cam and reservoir.

8. A grinding-wheel support, comprising a base, a water-reservoir, a link connection between the reservoir and base, a series of arms, a double cam moved by the arms, and a connection between the link connection and double cam.

9. A grinding-wheel support, comprising a base having an opening and a depending projection, the projection having an outwardly-extending flange, a water-reservoir receiving the projection and having an inwardly-extending flange overlying the outwardly-extending flange, and means for raising the water-reservoir.

BENJAMIN F. BARNES.
